*Primary Examiner—Brian N. Vinson**Assistant Examiner—Robin V. Tyler**Attorney, Agent, or Firm—Roger A. Marrs***[57]****CLAIM**

The ornamental design for adjustable nozzle for a pressurized container, as shown and described.

DESCRIPTION

FIG. 1 is a top, front perspective view of an adjustable nozzle for a pressurized container showing my new design;

FIG. 2 is a side elevational view thereof, the other side being a mirror image;

FIG. 3 is a front elevational view thereof;

FIG. 4 is a rear elevational view thereof; and,

FIG. 5 is a bottom plan view thereof.

FIG. 1.

FIG. 3.

FIG. 2.

FIG. 4.

FIG. 5
